US0D1064413S

(12) **United States Design Patent** (10) **Patent No.:** **US D1,064,413 S**
(45) **Date of Patent:** **** Feb. 25, 2025**

(54) **BACK SCRATCHER**

(71) Applicant: **Peng Zhang**, Shenzhen (CN)

(72) Inventor: **Peng Zhang**, Shenzhen (CN)

(**) Term: **15 Years**

(21) Appl. No.: **29/953,838**

(22) Filed: **Jul. 24, 2024**

(51) **LOC (15) Cl.** **28-99**

(52) **U.S. Cl.**

USPC **D28/91.2**

(57) **CLAIM**

The ornamental design for a back scratcher as shown and described.

DESCRIPTION

FIG. 1 is a front, right and top perspective view of a back scratcher showing my design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is an enlarged top plan view of the back scratcher; and,

FIG. 7 is an enlarged bottom plan view of the back scratcher. The broken lines are included for the purposes of illustrating portions of the back scratcher that form no part of the claimed design.

1 Claim, 7 Drawing Sheets
